ASSIGNORS, BY DIRECT AND MESNE ASSIGNMENTS, TO BENJAMIN P.
OBDYKE, INC., OF PHILADELPHIA, PENNSYLVANIA, A CORPORATION OF
DELAWARE.

SHEET-METAL-SEAMING MACHINE.

1,381,062.

Specification of Letters Patent. Patented June 7, 1921.

Application filed July 10, 1918, Serial No. 244,202. Renewed March 22, 1921. Serial No. 454,418.

To all whom it may concern:

Be it known that we, JOHN W. BROWN and WILLIAM HESS, citizens of the United States, residing at Philadelphia, in the county of Philadelphia and State of Pennsylvania, have invented certain new and useful Improvements in Sheet-Metal-Seaming Machines; and we do hereby declare the following to be a full, clear, and exact description of the invention, such as will enable others skilled in the art to which it appertains to make and use the same.

This invention relates to improvements in seaming machines for forming locked joints on sheet tin or other like sheet material.

The object in view is the rapid, efficient and inexpensive completion of an interlocking seam formed of the overlapping edge portions of two sheets, the entire operation being automatic with the exception of the actual feeding of the sheets of material.

With this and further objects in view, as will in part hereinafter become apparent and in part be stated, the invention comprises certain novel constructions, combinations and arrangements of parts as subsequently specified and claimed.

In the accompanying drawings,—

Figure 1 is a view in front elevation of a machine embodying the features of the present invention.

Fig. 2 is a view in side elevation thereof, parts being broken away.

Fig. 3 is a transverse section taken on the plane indicated by line 3—3 of Fig. 1, the parts being in the position assumed when the sheets are first located for the beginning of an operation.

Figs. 4, 5, 6 and 7 are views similar to Fig. 3, showing the successive steps of the operation of completing a seam and leaving the sheets in the final position of the machine free for removal from the machine.

Fig. 8 is a horizontal section taken on the plane indicated by line 8—8 of Fig. 3 and looking downward.

In the accompanying drawings, 1 indicates a supporting framework in which are journaled the operating shafts carrying the actuating gear and connected with the operating cams hereinafter described. Forming a part of the framing 1 is the horizontal table 2 having a longitudinal slot or opening in which is arranged the plunger 3,

said plunger being guided by the walls of the slot and being actuated by a cam 4, fixed to a shaft 5 in the framing 1 and carrying an operating gear 6 meshing with a gear 7, which latter gear is mounted on the drive shaft 8. Drive shaft 8 is provided with the usual tight and loose pulleys and supplied with power through a belt 9. Of course, the power supplied to shaft 8 may be otherwise delivered.

Above the table 2 are arranged the laterally-reciprocating tuckers 10 which are slidably mounted between the side plates of the framing 1. Each tucker 10 is guided at its inner portion by endwise extending pins 11 projecting into guiding slots 12 formed in the side plates of the framing 1. Similar pins 13 extend endwise from the outer portion of each tucker 10, and each extends through the respective slot 12 and into the cam groove 14 formed in the face of an actuating gear 15 meshing with a gear 16 fixed to the drive shaft 8. There are thus four gears 15, two at each side of the machine, arranged in pairs, and the gears of each pair are connected and supported by a shaft 15' which is journaled in the side plates of framing 1.

Above the table 2, and extending lengthwise thereof substantially in line with the plunger 3, is a plunger 17, which, because of its functions, we preferably designate as a hammer. At each side of this hammer is arranged a folder 18, each slidably mounted between the hammer and a guide plate 19 forming part of the framework 1. The folders 18 may be operated by independent cams, but as their movement is identical, it is preferable to actuate them from a single cam, and, therefore, the folders are connected at their ends. One of the folders is provided with a connecting rod 20 at each end extending to and engaging a cam 21 of cam gear wheel 22. The gear wheels 22 are fixed to a shaft 25 and mesh with cam gear wheels 23 fixed to a shaft 24 journaled in the framing 1. The gears 23 mesh with gears 16. The hammer 8 is provided with connecting rods 26 engaging cams 27 of the gear wheels 23.

The operation consists in introducing a sheet in position lying with its edge portion extending across the plunger 3 and placing a second sheet to have its edge portion lap

the first sheet, as indicated in Fig. 3. Then the folders 18 move down to the position indicated in Fig. 4, and the plunger 3 immediately thereafter moves up to the position indicated in Fig. 4, so that the lapping portions of the sheets are caused to assume an inverted trough-like shape. The folders then move upward and the plunger 3 moves downward. Then the tuckers 10 move inward to the position indicated in Fig. 5 for drawing the sheets toward each other and producing an underhanging of the vertical walls of the trough-shaped portion. The tuckers 10 then move outward and the hammer 17 descends upon the upstanding portion of the sheets and crushes them to the position indicated in Fig. 6. Then the hammer moves upward and the parts assume the position indicated in Fig. 7. The parts remain in this position until the sheets are slid out from beneath the operating parts and are ready for a second operation.

It is, of course, obvious that where a series of sheets are to be connected, one edge of a sheet is seamed to an edge of another sheet, and then the two sheets are moved along the table until the second edge of the first-mentioned sheet is located over the plunger 3, and a new sheet is positioned for being seamed thereto, and so on until a strip of tin or other sheet material is produced of any required length.

What we claim is:—

1. In sheet metal seaming machines, the combination with a frame having a slotted supporting table, of a plunger reciprocally-mounted in the slot and adapted to have its upper end move upward beyond the plane of the table and to be sustained in the elevated position in timed relation to move-

ments of other parts, reciprocating folders movably mounted at opposite sides of the plunger when elevated, laterally-disposed tuckers arranged when elevated in the planes of the lower ends of the folders when elevated, and means for moving the tuckers laterally inward toward each other and simultaneously moving the inner portions of the tuckers downward substantially to the plane of the table upon withdrawal of the plunger and folders. 45

2. In sheet metal seaming machines, the combination with a frame having a slotted supporting table, of a plunger reciprocally mounted in the slot and adapted to have its upper end move upward beyond the plane of the table and to be sustained in the elevated position in timed relation to movements of other parts, reciprocating folders movably mounted at opposite sides of the plunger when elevated, laterally-disposed tuckers arranged when elevated in the planes of the lower ends of the folders when elevated, the tuckers being movable laterally inward toward each other and downward 60 substantially to the plane of the table when the plunger and folders are withdrawn, the frame being formed with guiding slots, guiding pins extending from the tuckers into the slots for guiding the tuckers in 65 their inward and downward movement, and means for thus reciprocating the tuckers. 70

In testimony whereof we affix our signatures in presence of two witnesses.

JOHN W. BROWN.
WILLIAM HESS.
